ROTARY PUMPING APPARATUS

Peter M. Riede, Buffalo, N. Y., assignor to The
Linde Air Products Company, New York, N. Y.,
a corporation of Ohio

Application July 10, 1942, Serial No. 450,381

3 Claims. (Cl. 103—96)

1

The present invention relates to a method and apparatus for pumping highly volatile liquefied gases having a boiling point temperature at atmospheric pressure below 273° K. It is of particular advantage in the pumping of liquid oxygen which has a boiling point at atmospheric pressure considerably below 233° K.

In the transfer and supply of liquid oxygen for industrial use there is a need for a pump capable of producing pressures of 200 pounds and upwards, a desirable operating range being from about 100 to 350 pounds per square inch. The capacity of a pump to be used for such purposes should be relatively high as, for example, a discharge rate in excess of 100,000 cubic feet per hour measured as gas at normal temperature and atmospheric pressure. The conditions commonly require intermittent operation and, accordingly, the priming time should be short, and complete automatic operation without more than infrequent attention is very desirable. Also in general the construction should be light weight, compact and simple in order to minimize vaporization and the consequent interference with operation and loss of oxygen material.

The present invention is directed to the problem of meeting these and other criteria. It involves the special design of a multi-stage rotary pump employing impellers of the character known as turbine type, having a series of blades at the periphery extending radially inwardly for a short distance only, adapted to move in an annular channel extending around and enclosing the bladed periphery for nearly its entire extent. Of particular importance is the matter of correlation of size and speeds of the impellers both as respects the individual impellers and their relation to each other, whereby there is accomplished an efficiency and dependability of operation in connection with the handling of liquefied gases exemplified by liquid oxygen which, it is believed, has not heretofore been attained.

Other objects of the invention will in part be obvious and will in part appear hereinafter.

The invention accordingly comprises the several steps and the relation of one or more of such steps with respect to each of the others, and the apparatus embodying features of construction, combinations of elements and arrangement of parts which are adapted to effect such steps, all as exemplified in the following detailed disclosure, and the scope of which invention will be indicated in the claims.

For a fuller understanding of the nature and objects of the invention reference should be had

2

to the following detailed description taken in connection with the accompanying drawing, in which:

Fig. 1 is a view in elevation of a pump and power operating means representative in general of the invention;

Fig. 2 is a cross-sectional view in elevation showing details of the pump interior, including in particular the rotary impellers; and

Fig. 3 is an irregular cross-sectional view of the pump casing taken on the line 3—3 of Fig. 2 but with the rotary parts omitted.

The results of my discoveries forming the subject matter hereof are exemplified in the drawings showing a multistage pumping means employing impellers of the turbine type, the sizes and speeds of operation of which and their relation to each other will be discussed hereinafter.

In a pump of this character it has been found that by proper correlation a major increase in pressure may be attained in a second stage which is considerably greater than that possible in the first stage of such a pump or in a single stage pump of similar character. That is to say, the

rise in pressure possible in the second stage is far in excess of the rise in pressure in the first stage, this is more specifically illustrated by the fact that although the maximum pressures obtainable under normal conditions with a single stage pump

of the type here considered are materially less than 100 pounds per square inch; yet a two stage pump constructed and operated in accordance with the principles of the invention will produce pressures of 350 pounds and upwards. The values given are for liquid oxygen. The rise in pressure in the second stage and the maximum final pressure are, however, dependent upon the character of the first stage as well as that of the second stage. It has been discovered that within

reasonable limits of impeller diameter the best results are obtained when the peripheral speeds of the impellers are maintained within certain limits, respectively, and that the peripheral speed of the high pressure stage should be considerably greater than that of the low pressure stage. Continuing with the statement of conclusions in this respect it has been found that the objectives may be attained in a pump having a first stage impeller of the type heretofore noted operating at

a peripheral speed generally within the range of 2,000 to 3,000 feet per minute; and a second stage having a similar type impeller operating at a peripheral speed in the range of about 3,200 to 4,500 feet per minute. In general the peripheral speeds are preferably such that the peripheral

speed of the second stage impeller is about one-quarter to one-half greater than that of the first stage impeller.

As a specific example of results obtained, two turbine type pumps separately driven but connected in series were operated, the impellers of each being six inches in diameter. The optimum speeds were about 1,600 R. P. M. for the first stage and about 2,700 R. P. M. for the second stage, which, in terms of peripheral speed, may be expressed as approximately 2,500 feet per minute for the first stage and 4,200 feet per minute for the second stage. Peripheral speeds for the first stage over a range of approximately 2,000 to 3,000 gave good results, although not quite as good as within the range of about 2,200 to 2,830 feet per minute (1,400 to 1,800 R. P. M.). With the first stage pump operating at 1600 R. P. M. good results were obtained over a fairly wide range of speeds of the high pressure stage, the optimum however being, as stated, around 2,700 R. P. M., which gave a discharge pressure of well over 300 pounds per square inch. The delivery rate varied with the pressure but was relatively high throughout the range of pressures tested.

In a turbine pump arrangement employing a low pressure impeller about eight inches in diameter, the optimum speed was about 1,200 R. P. M. which gives the same peripheral speed as that of a six inch diameter impeller operating at 1,600 R. P. M. referred to above.

The general principles and conclusions may be illustrated by other examples. With a six inch diameter first stage impeller and an eight inch diameter for the higher pressure stage with both impellers operating at 1,750 R. P. M., a pressure of 350 pounds per square inch was easily attained.

As heretofore noted, a range of peripheral speeds for the second stage may be given as generally between about 3,200 and 4,500 feet per minute, although a preferred range would comprise about 3,600 to 4,200 feet per minute. The diameter for the first stage impeller should be preferably in the range of five to nine inches, and for the next or higher stage a diameter in the range of six to ten inches. These diameters contemplate, of course, appropriate R. P. M. respectively, and when both impellers are mounted on the same shaft the impeller for the higher pressure stage will be larger than that of the low pressure stage.

It will be understood that the pressures mentioned are with liquid oxygen having a relatively low viscosity. It will also be understood that if still higher ultimate pressures are desired further stages may be added, and that the values and description given herein refer to the first two stages of a pump.

In the drawings there is depicted a specific arrangement illustrative of the principles of the invention. It comprises a two-stage turbine type pump with both impellers mounted on the same shaft but of unequal diameter to result in different peripheral speeds for the two stages. The general arrangement as shown in Fig. 1 includes a pump 10 having a tubular extension sleeve 11 for the drive shaft with an outer seal 12. The drive shaft 13 is provided with a suitable outboard bearing shown generally at 14 mounted on a supporting bracket 15. The source of power is indicated as an electric motor 16 connected directly to the pump shaft 13 by a suitable coupling 17.

An intake to the first stage is shown at 28, which for good results on liquid oxygen will be connected to a source of supply adapted to pro-

vide a moderate pump intake pressure such as that of a head provided by an elevated supply tank giving a gravity flow of liquid to the pump inlet. The liquid is discharged from the first stage at the outlet 21 from which it is led through pipe 22 to the inlet to the higher pressure stage and is discharged from there at the outlet 23.

Referring now to Fig. 2, the pump has a main casing 25 provided with a cover plate 26 at the left end, and a further cover plate 27 at the right, each of these cover plates being secured in place by suitable means such as cap screws. The end plate 26 is provided with an extending tubular portion 28 in which is secured the shaft enclosing sleeve 11. The end plate 27 also has an enlarged tubular extension 29 enclosing the inner end of the drive shaft, a small plate 30 being secured to the outer end of the extension 29 by suitable means such as cap screws to provide a tight seal.

The specific drive means and the bearing arrangements may be varied, but that shown illustrates one having particular advantages with respect to the avoidance of leakages and reduction of friction and vaporization of the liquid oxygen.

As specifically shown, the shaft 13 is provided with a portion having splines 33 adapted to drive the low pressure stage impeller 34 and the high pressure stage impeller 35. The impeller 34 has an axially elongated hub portion 36 provided with keyways adapted to receive the shaft splines 33. Likewise the impeller 35 has an elongated hub sleeve portion 37 extending to the right provided with keyways adapted to receive the splines 33. The inner or right-hand of the sleeve 37 is provided with a combined closure and sleeve portion 38 threaded into the interior of the sleeve 37, the part 38 having a bearing on the inner smooth end portion 39 of the shaft 13. The shaft is freely slideable as to each of the impellers, the latter being designed to float thereon independently of each other.

As heretofore noted, the impellers are of the turbine type having blades arranged at the periphery designed to operate in pumping channels extending for nearly the entire circumference of the respective impellers and, accordingly, the impeller 34 is provided with milled out slots 41, there being similar alternate slots on each side of the impeller adapted to propel the fluid through the channel 42 located in the main housing part 25. Similarly the impeller 35 is provided with milled out slots 43 on the opposite sides of its peripheral portion, which operates in the pumping channel 44. The milled out slots are such as to result in suitably spaced vanes or blades arranged in accordance with impellers of this type.

In Fig. 3 there is shown a broken away view in cross-section of the pumping channel of the low pressure stage. It is important to avoid turbulence or undue restriction particularly in the inlet to the first stage and accordingly as shown in Fig. 3 the inlet to the pumping channel for the first stage is of smooth contour and of gradual reduction in size. A similar shape is preferably employed at the outlet. As shown in Fig. 3, the pumping channel 42 is provided with a partition 44a suitably shaped in accordance with the provision of a smooth inlet and outlet, and which also serves the purpose of dividing the outlet from the inlet, the partition 44a comprising in substance a raised flat portion projecting toward the lateral face of the bladed portion of the impeller 34. The end plate 26 is provided with a similar channel and partition part complementary to the channel 42 and partition part 44a shown in Fig. 3.

The outer edge of the channel 42 is drawn inwardly at the region 42a so that with the projecting portions 44a the channel at this region is reduced to substantially the size of the bladed portion of the impeller with but a few thousandths of an inch clearance. The arrangement of the high pressure stage pumping channel is similar to that of the low pressure stage illustrated, except being displaced in general 180 degrees therefrom.

The hub portion 36 of the impeller 34 is located between two bearing rings 46 and 47 which determine the axial position of the impeller, the hub having a slide fit on the splined shaft whereby the impeller in effect floats thereon. The bearing ring 46 at the left is located in and supported by the cover plate 26 and the bearing ring 47 at the right is carried by the ring 48 which is threaded into an annular recess in the main housing 25.

The axial position of the impeller 34 may be adjusted through adjustment of the ring 48 and by the use of annular shims wherever appropriate, as adjoining one or both of the bearing rings 46 and 47, and also if desired at the point 49 between the main housing 25 and the end plate 26.

As heretofore noted, the impeller 35 is rotated through the spline connection with the drive shaft 13 but similarly to the impeller 34 is designed to float freely thereon in an axial direction. Fitted within the tubular extending portion 29 of the end plate 27 is an annular bearing sleeve 51 which serves as a radial support for the impeller sleeve 37 and in turn forms an inner radial bearing support for the drive shaft 13. The annular bearing sleeve 51 is secured against endwise movement at one end by the ring 52 secured in the housing part 25 by suitable means as by the screws 53 and at the opposite end by the annular sleeve 54 formed on the end cover plate 30.

The impeller 35 bears at the left against an annular thrust bearing ring 56 located in a supporting ring 57 threaded into an annular recess in the housing part 25. The impellers 34 and 35 are provided with openings 58 and 59 respectively permitting balancing of fluid pressures therethrough. In the case of impeller 35, however, fluid pressure derived from the pumping channel 44 acting on the greater area on the right-hand side of the hub portion serves to urge the impeller to the left against the thrust bearing 56, which has the combined result of maintaining the impeller in correct axial position against the thrust bearing ring 56, and, in addition, the engagement of the surfaces effects a seal against leakage of the liquid from the high pressure stage into the low pressure stage. Axial adjustment of the impeller 35 may be effected by adjustment of the ring 57 or by the use of shims on either side of the thrust bearing 56.

In connection with the axial adjustment of the two impellers it may be noted that the pumping channel 44 is defined at its inner part by the ribs 60 and 61 formed on the complementary housing parts. The impeller is designed to have a running fit between these two rib parts, a clearance of a few thousandths of an inch being provided on each side. The impeller 34 is similarly positioned between the ribs 62 and 63.

It will be noted that the inner end of the shaft and all of the bearings within the pump housing are completely enclosed and sealed within the housing resulting in a pump casing free of leakage. This is made possible particularly by the use of bearing members, in this case the thrust bearings 46, 47 and 56 and the radial bearing 75

51 of a character which are self-lubricating, not requiring the application of any auxiliary lubricant, such as hydrocarbons, from the exterior. Also the material employed for the bearings is inert to liquid oxygen. A bonded graphite which may be impregnated, if desired, with suitable materials has been found especially effective for the purpose described.

The sealing means against leakage of oxygen material is located at 42 at the outer end of the extended sleeve 41. The specific construction of the seal may vary and details are not disclosed herein, but in general it may advantageously be of the type employing an expansion bellows engaging against a bearing ring of a material similar to the thrust bearing rings located on the interior of the pump housing. With the arrangement illustrated the leakage of heat into the pump is reduced to a minimum and the rubbing parts of the seal may be kept reasonably warm.

The pump impellers are of a diameter and the intended speed of operation are in accordance with the values and relation to each other described in the early part hereof. A particularly efficient arrangement is one employing a low pressure stage impeller 34 having an outer diameter of about six inches and a high pressure stage impeller having an outer diameter of about nine inches. With a standard electric motor having a direct drive connection to the pump shaft 13, operated at 1,750 R. P. M., the low pressure impeller will have a peripheral speed of about 2,750 feet per minute and the high pressure impeller will have a peripheral speed of about 4,125 feet per minute. Such a pump is capable of delivering liquid oxygen at pressures well above 300 pounds per square inch if necessary. Its capacity is also relatively high within pressures normally required.

Since certain changes in carrying out the above method and in the constructions set forth, which embody the invention may be made without departing from its scope, it is intended that all matter contained in the above description or shown in the accompanying drawing shall be interpreted as illustrative and not in a limiting sense.

Having described my invention, what I claim as new and desire to secure by Letters Patent, is:

1. In a multi-stage rotary pumping means for pumping liquefied gases having a boiling point at atmospheric pressure below 273° K., having stages of relatively low and high pressure suitably connected by fluid conduits, a rotary impeller of the turbine type with blades at the periphery thereof for each of said stages, a driving shaft, said impellers being axially spaced thereon, casing means providing an annular fluid pumping channel for each impeller enclosing the bladed peripheral portion thereof respectively, the diameter of the impeller and its channel for the high pressure stage being substantially greater than that of the lower pressure stage and said high pressure impeller having thereby a greater peripheral speed.

2. In a multi-stage rotary pumping means for pumping liquefied gases having a boiling point at atmospheric pressure below 273° K., said means having stages of relatively low and high pressure suitably connected by fluid conduits, a rotary impeller of the turbine type with blades at the periphery thereof for each of said stages, a driving shaft with power means for operating it, said impellers being mounted in axially spaced rela-

tion on said shaft, and casing means providing an annular fluid pumping channel for each impeller enclosing the bladed peripheral portion thereof respectively, the diameter of the low pressure impeller and the speed of the driving means being such that the peripheral speed of the low pressure impeller is within the range of 2,000 to 3,000 feet per minute, and the diameter of the high pressure impeller being substantially greater than that of the lower pressure stage and having thereby a greater peripheral speed.

3. In a multi-stage rotary pumping means for pumping liquefied gases having a boiling point at atmospheric pressure below 273° K., said means having stages of relatively low and high pressure suitably connected by fluid conduits, a rotary impeller of the turbine type with blades at the periphery thereof for each of said stages, a driving shaft with power means for operating it, said impellers being mounted in axially spaced relation on said shaft, and casing means providing an annular fluid pumping channel for each impeller enclosing the bladed peripheral portion

thereof respectively, the diameter of the low pressure impeller and the speed of the driving means being such that the peripheral speed of the low pressure impeller is within the range of 2,000 to 3,000 feet per minute, and the diameter of the high pressure impeller being sufficiently greater than that of the lower pressure stage to provide a peripheral speed within the range of 3,200 to 4,500 feet per minute.

PETER M. RIEDE.
